UNITED STATES PATENT OFFICE.

FREDERICK F. BUCHANAN AND NEWMAN F. SLACK, OF MACHIPONGA, VIRGINIA.

PACKAGE-TIE.

1,353,717.

Specification of Letters Patent. Patented Sept. 21, 1920.

Application filed April 4, 1916. Serial No. 88,835.

To all whom it may concern:

Be it known that we, FREDERICK F. BUCHANAN and NEWMAN F. SLACK, citizens of the United States, residing at Machiponga, 5 in the county of Northampton and State of Virginia, have invented certain new and useful Improvements in Package-Ties; and we do hereby declare the following to be a full, clear, and exact description of the invention, such as will enable others skilled 10 in the art to which it appertains to make and use the same.

The invention relates to improvements in package ties.

15 The object of the present invention is to improve the construction of package ties and to provide a simple, practical and efficient package tie of strong and durable construction adapted to be readily manufactured and equipped with means for clamping the cord or other flexible connection as the successive portions are placed in or around it whereby the cord is prevented from accidentally slipping both when placing 20 the package tie around the package and in the final tying of the cord.

25 A further object of the invention is to provide a package tie of this character which may be readily removed from a package without injuring the device whereby the latter may be used a number of times.

With these and other objects in view, the invention consists in the construction and novel combination of parts hereinafter fully 30 described, illustrated in the accompanying drawing, and pointed out in the claim here-to appended; it being understood that various changes in the form, proportion, size and minor details of construction, within 35 the scope of the claim, may be resorted to without departing from the spirit or sacrificing any of the advantages of the invention.

In the drawing—

40 Figure 1 is a plan view of a package tie constructed in accordance with this invention and shown applied to a package,

Fig. 2 is a longitudinal sectional view on the line 2—2 of Fig. 1,

45 Fig. 3 is a transverse sectional view on the line 3—3 of Fig. 1,

Fig. 4 is an enlarged plan view of the package tie illustrating the manner of

clamping the cord after the latter has been passed around the package in one direction 55 and is turned to extend it in the opposite direction or at right angles,

Fig. 5 is an enlarged detail perspective view of the fastening device.

Like numerals of reference designate 60 corresponding parts in the several figures of the drawing.

In the accompanying drawing in which is illustrated the preferred embodiment of the invention, the package tie comprises in its 65 construction a fastener 1 constructed of a single piece of resilient wire or other suitable material bent at a point between its center and one end to form an eye 2 which is adapted to have one end 3 of a cord 4 or 70 other suitable flexible connection tied to it, the cord 4 being passed through the eye and knotted in any suitable manner.

The wire at one side of the eye 2 is bent back and forth longitudinally of the 75 fastener to form spaced approximately U-shaped loops 5 and 6 and a connecting bend 7. The approximately U-shaped loops constitute the sides of the fastener and the other terminal portion of the wire is extended longitudinally of the fastener from the said eye 2 to form a resilient clamping tongue 8 which is located between the sides of the fastener and which is adapted to clamp the free portion of the cord 4 as the 80 same is introduced into the fastener in placing the said cord around a package 9 and also in making the final tie of the cord after the package has been wrapped.

In applying the cord 4 to the package 9 90 the fastener is placed against the center of the package at one of the side faces or the top side face thereof and the cord is then passed around the package longitudinally and the free portion is drawn transversely 95 through the fastener between the upper and lower sides of the two approximately U-shaped loops and then the direction of the cord is changed to pass it transversely around the package at right angles to the 100 longitudinal loop, or package encircling portion. It is then drawn through the loop and passed around the end of the fastener and back of the projecting terminal 10 of the clamping tongue so that there will be no 105 liability of the cord accidentally slipping

out of the fastener. The clamping tongue engages the cord and coacts with the side loops which constitute the body portion of the fastener. The package tie is adapted to be readily applied to a package and is capable of being easily and quickly removed therefrom without injuring the fastener and when one cord has worn out another may be substituted for the worn cord.

10 What is claimed is:—

A package tie comprising a single wire bent to form an eye and a fixed jaw and

spring jaw, the fixed jaw extending substantially to the eye and the spring inclined directly upward from the eye to yieldingly 15 oppose the fixed jaw.

In testimony whereof we affix our signatures in the presence of two witnesses.

FREDERICK F. BUCHANAN.
NEWMAN F. SLACK.
